R. D. KELLY

WATER WHEEL

Filed Aug. 10, 1922

UNITED STATES PATENT OFFICE.

RICHARD D. KELLY, OF THE DALLES, OREGON.

WATER WHEEL.

Application filed August 10, 1922. Serial No. 580,843.

To all whom it may concern:

Be it known that I, RICHARD DAVID KELLY, a citizen of the United States, residing at The Dalles, in the county of Wasco and 5 State of Oregon, have invented a new and useful Water Wheel, of which the following is a specification.

My invention relates to improvements in submerged water wheels with a vertical 10 shaft and radially extending blades, said blades presenting a broad surface when moving with the current and an edge when moving against the current.

The objects of my invention are:—

15 First, to produce a wheel which moves entirely under water and is therefore not affected by a rise in the water level.

Second, to produce a wheel which turns the blades automatically through an angle 20 of 90 degrees, so that one half of the total number of blades receives the full force of the current while the other half cuts edge- 25 wise through the opposing current.

Third, to produce a wheel which can 30 easily be lifted out of the water, and therefore facilitates repair.

Other objects and advantages are to be found in the construction and arrangement of parts as will be described hereinafter.

35 I attain these objects with the mechanism illustrated in the accompanying drawing in which:—

Fig. 1 is an elevation of the entire mechanism with part of the foundation and thrust bearing shown in section.

Fig. 2 is a section through Fig. 1 along the line 2—2.

Similar numerals refer to similar parts throughout the several views.

40 The platform 1 may be supported on structural steel members 2 and concrete foundations 3, or otherwise on piles driven into the river bed 4. Centrally to the supporting members on the river bottom is a concrete slab 5 into which is embedded a vertical shaft 6, said shaft extending beyond the upper surface of the platform. Concentrically to the shaft 6 and also attached to the concrete slab 5 is a thrust bearing 7

45 which furnishes the support for a pipe sleeve 8. Said pipe sleeve is rotatively mounted in the platform and has attached to the upper end, above the platform, whatever pulleys or gears 9, may be needed to drive the desired machinery on the platform. Also attached to the pipe sleeve 8,

but below the low water level 10 is a hub 11 from which radiate the arms 12 for the blades 13. Said arms are rotatively mounted in the hub 11 and retained therein by 60 washers 14 and pins 15. Affixed to each arm between the blade and the hub are two rectangular blocks 16 and 16' which are set with their longitudinal axes at right angles to each other and perform a function akin 65 to gear tooth and shoe combined.

A circular track 17 underneath the blocks is supported on standards 18 on the concrete slab 5. A step at the outer periphery of said track is adapted to trip at the proper 70 time the block nearest the blade, while another step diametrically opposite but at the inner periphery trips the block nearest to the hub.

Illustrating this operation by means of 75 Fig. 2, the current is supposed to rotate the water wheel in the direction of the arrow 19. As the block 16 approaches the step 20 on the track 17, said block is tripped from a vertical to a horizontal position and continues to slide as a shoe with the long edge on the circular track; the blade has thereby been turned to a vertical position and is retained therein as long as the block or shoe remains in gliding contact with the track. 80 Arriving at the diametrically opposite side of the circular track, the step 21 trips the shoe 16', while the shoe 16 is clear off the track, and therefore able to rotate through 85 an angle of 90 degrees. The blade 13 assumes a horizontal position and cuts edge- 90 wise through the opposing current. The steps 20 and 21 are cut slantingly to give a better leverage on the shoe and to facilitate the rotation of the blades around the 95 arm.

In case of repairs, the pipe sleeve with its attached blades can be lifted out of the water by means of suitable hoisting rigs, whereby the shaft 6 helps to keep the wheel 100 from swaying. After the repair is made the shaft guides the pipe sleeve to a proper bearing, and besides retains the surfaces of the bearing members in proper alinement during the rotation.

105 This machine may be used to drive pumps for irrigation purposes or as a power plant for industrial purposes, and will remain serviceable when high water forces the rearrangement or even discontinuance of other 110 water wheels.

Having thus described my invention it

will be seen that my objects have been accomplished, and, though I have shown the preferred form of construction I reserve to myself the right to make minor changes providing I do not violate the spirit and principle of my invention.

I claim:

In a water wheel, the combination of a platform, a foundation mounted underneath the platform, a pipe sleeve rotating on the foundation and extending through the platform, arms radiating from the pipe sleeve and having an independent rotation around

their axis, blades mounted at the end of the arms, an inner shoe mounted on each arm near the pipe sleeve, an outer shoe mounted on each arm near the blade, a track supported on the foundation underneath the shoes, and steps in the track adapted to alternately engage the inner and outer shoes, whereby the blade is compelled to change its relative position. ¹⁵ ²⁰

Signed by me at Portland, Oregon, this 3rd day of August, 1922.

R. D. KELLY.
